HOISTING CABLE ATTACHMENT

John A. Spisak, East Pittsburgh, Pa.

Application February 1, 1944, Serial No. 520,660

3 Claims. (Cl. 242—117)

The present invention relates to improvements in means for attaching hoisting cables to winding drums, and aims to provide confining means effective to prevent the cable end from being thrown outwardly by centrifugal force upon rotation of the drum.

While not limited thereto, the present invention is peculiarly well suited for anchoring haulage cables to the drums used to propel the skip cars used in charging modern blast furnaces.

The invention will be fully apparent from a consideration of the following detailed description and claims when read in connection with the accompanying drawings, in which:

Figure 1 is an elevation of a blast furnace showing a skip car for charging the same, the car being connected by cables to a hoisting drum embodying the present invention.

Figure 2 is an enlarged plan view of the drum shown in Figure 1.

Figure 3 is a section on line III—III of Figure 2.

Figure 4 is a similar section on line IV—IV of Figure 2.

Figure 5 is a fragmentary detail on line V—V of Figure 3.

Referring in detail to the drawings, reference numeral 10 represents a conventional form of blast furnace having the usual charging bells 12 and 14 and charging hopper 16. An inclined track 18 is traversed by skip cars 20 and 22. These cars are so connected with their haulage cables and with the hoisting drum indicated generally at 24 that when the skip car 20 ascends the inclined track 18, the companion car 22 descends. These cars are arranged to automatically dump the material into the charging hopper 16 at the top of the furnace. Occasionally the length of the cable must be adjusted due to stretch or other causes. The present invention provides an extremely simple yet effective means for taking up slack in the cable to compensate for stretch. In conventional blast furnace skip car operation it is important that any adjustments made in the cable lengths be made with great haste so as to avoid as much as possible the delay to furnace operation. According to prior art practice, adjustments are made hurriedly and require the services of six workmen: two workmen for blocking the skip cars, two workmen outside the drum to force the cables through holes in the interior of the drum, and two workmen of small stature to crawl into the drums through the small spaces between the drum spokes to clamp the ropes within each drum. After

clamping the ropes near the entering holes, the cables are dragged through the spokes to the outside end of the drum, where the excess cable is burned off. For reasons of safety, burning equipment is not permitted to be used within the drums. The cable ends are then returned to the interior and intertwined about the drum spokes and clamped thereto in a manner to prevent the ends from fraying and whipping about. It is important that the loose ends be prevented from fraying, since the tendency of centrifugal force is to cause the cables to whip about. Such loose ends have been known to present a tangled, hairy mass of loose wires which constitute a serious danger to workmen in the vicinity of the drum.

My invention provides means for simplifying the operation of anchoring the cable to the drum, and also provides for confining the loose ends of the cable so as to prevent it from fraying and whipping about. As best shown in Figures 2 to 5 inclusive, my invention contemplates a somewhat standard form of drum, including complementary sections 26 and 28 separated by a spacer section 30, the spacer having annular flanges 32 and 34 seated in grooves 36 and 38 of the drum sections 26 and 28. One pair of cables 40 is wrapped around one drum section 26, and a similar pair of cables 42 is wrapped around the other drum section 28. The cables 40 are coiled on the drum in a direction opposite the coiling of the cables 42. Thus as the drum rotates one pair of cables will be wound upon the drum and thus cause the skip car 20 to ascend, while the other pair will unwind and cause the skip car 22 to descend. The means for securing all of the cables 40 and 42 to the drum are substantially identical; thus a description of the means for securing one end of a cable to the drum will be deemed sufficient, it being necessary, for the purpose of this disclosure, to note only that the individual cables on each drum may be anchored at their ends to the drum in any desired spaced relationship by suitably spacing the apertures 44 which are formed in the annular rim of the drum.

The free end of each haulage cable is passed through an appropriate aperture 44 and thence in a direction substantially parallel to the axis of rotation of the drum, through an opening 46 formed in an end web 48 constituting part of the drum section. The openings 46 are aligned with similar openings 50 formed in flanges 32 and 34 of the spacer member 30. Suitable anchorage clamps 52 are secured by bolts 54 to the free ends of each of the cables. The clamps 52 provide means for making adjustments to compensate for

slack in the cable. When the cable stretches, it is necessary merely to insert a pry bar between the clamp 52 and the flanges 32 or 34, so as to forcibly take up the slack. The clamps are then reset to a new position, and the free end of the cable is inserted in a tubular member 56 welded or otherwise secured to an arcuate bar 58 which is secured by bolts 60 to one of the flanges of the spacer member 38. The tubular member 56 confines the free end of the cable beyond the clamp and prevents it from whipping around and fraying out under the influence of centrifugal force as the drum rotates.

It will be apparent that with the arrangement described, there is a certain amount of surplus cable beyond the clamps 52. This permits of making minor adjustments when such are necessary or desirable. In practice, the cable ends are inserted through the openings 44 in the usual manner, the two workmen located inside the drums guiding the cable ends through the openings 46 and 50 to the inner end of the drum sections adjacent the web portions 48, whereupon the clamps 52 are readily attached. The cable ends, after being burned off to proper length, are inserted in the tubular members 56. Thereupon further work within the drum is unnecessary.

After cable adjustments and the securing of the clamps have been effected, eight segmental shields 62 and 62^a are secured in place, these being suitably perforated to fit over bolts 64 extended radially from blocks 66 which are welded or otherwise secured to the flanges 32 and 34 of the spacer member 38. The bolts 64 are spaced at suitable intervals, and certain of them, as indicated at 68, instead of being fastened to blocks 66, are carried by the same members 56 which support the tubular confining members 56. The shields 62 and 62^a serve as additional means for preventing the free ends of the cable from being thrown outwardly, as a safety precaution, in the event that the tubular members 56 become inadvertently loosened. The shields 62 are adapted to be readily removed without any undue delay, in order to expose any one of the several cable clamps 52. The shields will generally be numbered so that only those cables which require adjustment will be exposed. When the particular shield has been removed, it will be readily understood that adjustment of slack in the cable can be readily made from the exterior

of the drum, thus making it unnecessary for the workmen to enter the drum, as heretofore required, to make adjustments.

While I have described quite precisely the detailed features of construction and arrangement herein illustrated, it is to be understood that various modifications and substitutions of equivalents may be made by those skilled in the art without departure from the invention as defined in the appended claims.

I claim:

1. Hoisting apparatus comprising a pair of drums with a spacer member secured between them, respective cables coiled in opposite directions on each drum, the drums being apertured and the cable ends passing therethrough, respective anchorage clamps secured to end portions of each of said cables, respective tubular members secured to said spacer member and confining the free ends of the cables beyond the anchorages thereof, and segmental shields surrounding said spacer member and said tubular members, said shields being removably secured in assembled relation to said spacer member.

2. Hoisting apparatus comprising a drum having a haulage cable adapted to be wound thereon, the annular rim of the drum being apertured and an end portion of the cable passing therethrough, said drum having a radially-extending end web apertured to permit passage of the cable, a spacer member having a flange secured to said end web and being apertured to permit the passage of the cable therethrough, an anchorage clamp on the cable engaging said flange, and means secured to said spacer member at a point remote from said clamp for confining the free end of the cable beyond it.

3. Hoisting apparatus comprising a drum having a haulage cable adapted to be wound thereon, the annular rim of the drum being apertured and an end portion of the cable passing therethrough, said drum rim having an inwardly-extending end web apertured to permit passage of the cable, a spacer member having a flange secured to said end web and being apertured to permit the passage of the cable therethrough, an anchorage clamp on the cable engaging said flange, and a tubular member secured to said spacer member and surrounding the free extremity of said cable beyond said anchorage clamp.

JOHN A. SPISAK.
